CLAIM

I claim the ornamental design for a gas burner, as shown and described.

DESCRIPTION

FIG. 1 is a perspective view of a gas burner, showing a first embodiment of my new design;

FIG. 2 is a top plan view of FIG. 1;

FIG. 3 is a bottom plan view of FIG. 1;

FIG. 4 is a right-side elevational view of FIG. 1;

FIG. 5 is a left-side elevational view of FIG. 1;

FIG. 6 is a front elevational view of FIG. 1, the rear elevational view being a mirror image thereof;

FIG. 7 is a perspective view of a second embodiment of a gas burner;

FIG. 8 is a top plan view thereof;

FIG. 9 is a bottom plan view of FIG. 8;

FIG. 10 is a right-side elevational view of FIG. 8;

FIG. 11 is a left-side elevational view of FIG. 8; and,

FIG. 12 is a front elevational view of FIG. 8, the rear elevational view being a mirror image thereof.
